SUPPORT FOR A CANOPY OR THE LIKE

Milton Schwartz, Barrington, Ill., assignor to Carrols
Drive-In System, Inc., Chicago, Ill., a corporation of Illinois

Filed Nov. 30, 1959, Ser. No. 58,518

Term of patent 14 years

(Cl. D13—1)

FIG. 1 is a front elevational view of a support for a canopy or the like embodying my new design;
FIG. 2 is a left side elevational view thereof;
FIG. 3 is a rear elevational view thereof; and
FIG. 4 is a top plan view thereof.

I claim:

The ornamental design for a support for a canopy or the like, substantially as shown.
